UNITED STATES PATENT OFFICE.

TIMOTHY JOSEPH RYAN, OF DOUGLAS, ARIZONA.

DOOR-LOCKING ATTACHMENT.

Application filed June 27, 1925. Serial No. 40,027.

This invention relates to key rings and has for its principal object the construction of a combination article having the functions both of a key ring and theft foil. 5 the latter function being brought into play by hanging the key ring upon the shank of the door knob with an openable portion thereof extended to a position in which it passes through the eye of a key turned 10 crosswise in the keyhole of the lock with which the knob is associated, thereby preventing the key being turned, by manipulation from the opposite side of the door, to a position in which it can be forced out from 15 the keyhole and another key inserted for unauthorizedly unlocking the door.

Other objects of the invention will appear as the following description of an illustrative embodiment thereof proceeds.

20 In the drawings,

Figure 1 is a perspective view showing a door lock with the device of my invention in operative position as a theft foil.

25 Figures 2 and 4 are respectively side and end views in elevation of the key ring, with the keeper extended.

Figure 3 is a vertical elevation showing the device with the keeper closed.

Referring now in detail to the several figures, my novel key ring consists preferably of two parts, an open band portion 1 upon which the keys are strung, and a keeper 2 hingedly joined thereto by means such as the pivot 3. The free end of the keeper is 35 preferably latchably engageable with the adjacent end of the band portion 1, and while the latching means may be of any desired construction, I have shown the free end of the keeper bifurcated to form resilient lips 4, the latter being perforated, as indicated at 5, and springing over elevations 6 formed on the flattened faces 7 at the end of the band portion 1, when the keeper is snapped into closed position by pressure 45 of the thumb. Cooperating shoulders 8 and 9 on the portion 1 and keeper 2 act as a limit stop to prevent the keeper moving too far inward.

It is preferred to make the curvature of 50 the band portion 1 re-entrant at an intermediate point 10, so as to define two distinct lobes or loops 11 and 12. The slight elevation formed at the point 10 is of value in assisting to segregate in one of said loops 55 certain keys which the user of the device

may separate from the body of keys on the other loop, in his hunt for the desired key.

When it is desired to use the key ring as a theft foil, the keeper is moved to an extended position in which it may be passed 60 through the eye of a key turned crosswise in the keyhole when the key ring is hung by the loop 11, upon the door knob. As has been stated in an earlier paragraph, this prevents the key being turned with the 65 eye parallel to the keyhole, in which position it might be pushed out of the keyhole, by one working from the opposite side of the door.

It will be noted in the drawings that the 70 keeper is located to one side of a vertical line passing through the point of suspension of the key ring from the door knob, and that both the keeper and the adjacent parts of the band portion 1 are relatively 75 massive.

Ordinarily this would have a tendency to tilt the key ring and displace the keeper from its position within the eye of the key, particularly if the keeper were loosely pivoted. This tendency is overcome, however, in the present invention by making the loops 11 and 12 offset, as shown, the vertical line through the point of suspension of the key ring dividing the loop 12 into unequal parts, of which the greater is on that side of said line remote from the keeper. 80 This has the effect that in the ordinary gravitational disposition of the keys upon the loop 12, one or two more of the keys will 85 hang from the farther side of said loop than from side adjacent the keeper, counterbalancing the weight of the keeper and associated parts so that the position of the key ring shown in the drawings (Figs. 1 and 90 2) is its position of repose.

It is to be understood that numerous changes and alterations may be made in the shape and arrangement of the several parts, or in the substitution of mechanical equivalents for features herein shown and described, without departing from the scope 100 of the appended claim.

I claim:

A key ring including a band portion open 105 at one side and thereby providing upper and lower ends of the band portion, the lower end of the band portion being offset from the upper end, a keeper pivotally mounted on the offset lower end, said band 110

portion having a reinforced curvature on the side opposite the keeper forming an interior elevation which divides said band into distinct but communicating upper and lower loops, a lug projecting upwardly from the lower offset end of the band portion adapted to be engaged by the keeper when in operative position for closing the opening in the band portion for limiting the inward movement of said keeper, the lower offset end of the band portion being provided with shoulders adapted to engage with the keeper for maintaining the keeper when in open

position at an acute angle to the vertical passing through the pivoted point of the keeper so that the keeper may be inserted within an eye of a key when the key is placed in a lock for preventing turning of the key in one direction, the upper loop of the band portion being adapted to be engaged around the shank of a knob for supporting the key ring in position when the keeper has been located in the eye of a key.

TIMOTHY JOSEPH RYAN.
